Attest.

UNITED STATES PATENT OFFICE.

THOMAS D. WALLACE, OF ALLEGHENY, PENNSYLVANIA, ASSIGNOR OF ONE-HALF TO JESSE Y. SCOTT, OF WASHINGTON, PENNSYLVANIA.

LOCKING DEVICE.

SPECIFICATION forming part of Letters Patent No. 584,279, dated June 8, 1897.

Application filed February 1, 1896. Serial No. 577,744. (No model.)

To all whom it may concern:

Be it known that I, THOMAS D. WALLACE, a citizen of the United States of America, residing at Allegheny, in the county of Allegheny and State of Pennsylvania, have invented certain new and useful Improvements in Locking Devices, of which the following is a specification, reference being had therein to the accompanying drawings.

10 This invention relates to certain new and useful improvements in locking devices, and relates particularly to that class that are employed for the locking of satchels, telescopes, and the like.

15 The invention has for its object to construct a locking device for the above purpose whereby when employed on a telescope the same may be filled to any desired point and securely locked in such a manner that the contents 20 cannot be tampered with.

A further object of the invention is to provide a locking device which will strengthen the telescope when applied thereto; furthermore, a device that will permit of the dispensing with the straps ordinarily employed for fastening the lid or cover to the body portion.

25 A still further object of the invention is to construct a locking device that will be extremely simple in its construction, strong, durable, effectual in its operation, and comparatively inexpensive to manufacture.

With the above and other objects in view the invention finally consists in the novel construction, combination, and arrangement of parts to be hereinafter more specifically described, and particularly pointed out in the claims.

30 In describing the invention in detail reference is had to the accompanying drawings, forming a part of this specification and wherein like letters of reference indicate similar parts throughout the several views, in which—

Figure 1 is a perspective view of a telescope, showing my improved locking device in position. Fig. 2 is an end view of a telescope, showing one form of the graduated guide or rack. Fig. 3 is a similar view showing a different form of rack or guide. Fig. 4 is an end view showing a slight modification in the rack or guide. Fig. 5 is a cross-sectional view of the

cover. Fig. 6 is a perspective view of the brace of the cover. Fig. 7 is a sectional view of a portion of a telescope, showing the lock and their different parts in their position. 55 Fig. 8 is a view of a portion of the graduated rack, showing different form of hole. Fig. 9 is a sectional view of a part of the body portion of a telescope, showing the graduated rack in position.

In the drawings, *a* represents the body portion of a telescope, and *b* the lid or cover of the same. At the ends of the body portion *a* I have provided a graduated rack *c*, which also serves as a guide and is formed of one piece 65 of metal bent over the end wall of the telescope with the lower ends of the rack bent inwardly, as is shown in Fig. 9, where they can be riveted securely to the bottom of the telescope, thus holding the rack rigidly in position. 70

This rack and guide are provided with apertures or holes through both plates and through the telescope, and these holes are formed at an angle, as is fully shown in Fig. 7 of the drawings, the upper or higher end 75 of the holes being toward the top of the telescope. These holes are inclined to receive the hook, which swings in the arc of a circle, and also prevents a disengagement should the two sections of the telescope be separated. 80 The shell or plate *d* of the locking-bar is fastened to the cover in a position to correspond with the position of the rack, and in this plate or shell is secured the arm *e*, carrying at its lower end the locking-bar *f*. This locking-bar *f* is also inclined upwardly to correspond with the inclined apertures through the rack and the telescope-body, the construction of this locking-bar being fully shown in Fig. 7 of the drawings. This rack and guide 85 may be formed with the outer plate rounded at the edges, as is shown in Fig. 3, and in this construction the brace *g*, which is secured to the cover *b*, is provided with small lugs *g' g'*, which engage on the outer plate or guide of 90 the rack as the cover is being placed in position, and when the outer plate is formed with the groove or track, as shown in Fig. 4, the brace *g* is provided with a button *h*, which is adapted to ride in the groove or track formed 95 on the rack.

In Fig. 8 I have shown the holes in the rack

formed in an oblong shape, which construction may be employed, if desired.

The operation of my improved locking device will be readily apparent from the views 5 of the same which I have shown in the drawings.

Presuming that the parts of the device have been secured in their respective positions and the articles have been placed in the body portion 10 of the telescope, when the cover is placed over the contents and the body portion the locking-bar of the latch will be withdrawn, allowing the cover to pass over the contents and the body portion until the top of the 15 cover rests on the contents if the same are higher than the top of the body portion. The locking-bar is then forced into the aperture which it is opposite on the rack, and the spring 20 e', arranged in the shell or plate, will retain the same in position until it is withdrawn.

When the construction of guide formed on the rack, as shown in Fig. 3, is employed, the lugs formed on the brace g will engage the 25 rack as the cover is placed over the body portion, and should the groove, as shown in Fig. 4, be employed the button will engage in the groove or track during the same operation.

It will be observed that by the construction of the apertures and the locking-bar in the 30 form shown the locking-bar will be in engagement with the rack at the upper sides of the aperture.

These locking devices can be arranged at each end of the telescope and one or more 35 at the sides, as will be readily apparent, and the braces on the cover and racks on the body portion will serve to stiffen the telescope, thus making the same more serviceable. It will also be noted that when the contents of the 40 telescope do not reach farther than the top of the same the cover will fit down flat on the top as in the ordinary construction, and will be locked at the bottom, and when it is desired to pack the same to a greater extent 45 than level full the cover will rest on the contents and the locking-bar will engage in the rack at the point at which it is opposite. This construction of a locking device for a telescope will also obviate the necessity of the 50 ordinary securing or strengthening straps, thus allowing the telescope to be opened and closed much more readily than at present.

It is my intention to use on one of these locks the invention heretofore referred to as 55 applied for by me, thus securely locking the telescope and preventing the tampering with

the contents of the same, and it will be observed that when this lock is employed and is secured, I will say, to one end of the telescope it will be impossible to lift the other end 60 up sufficiently to remove any of the contents, as is often the case under the ordinary construction. Another advantage that may be mentioned in this connection is when the lock is employed a small chain may be used 65 for fastening the telescope to the leg or arm of a car-seat when traveling, and when the locking-bar is placed in position to lock it may be inserted through one of the links of the chain, which will keep any one from stealing 70 the same or taking it by mistake, as often happens.

It will be noted that various changes may be made in the details of construction of my improved locking device without departing 75 from the general spirit of my invention.

Having fully described my invention, what I claim as new, and desire to secure by Letters Patent, is—

1. In a locking device for a telescope or the like, a rack engaging the outer and inner surface of the telescope, said rack having its lower ends bent inwardly and secured to the bottom of the telescope, a brace secured on the inner face of the cover at a point opposite 85 the rack, and a plate or shell carrying a locking-bar secured to the cover, said locking-bar being adapted to engage apertures in the rack, substantially as shown and described.

2. In a device of the character described, a 90 body having a rack secured to its ends, inclined apertures through the rack and body, and a locking-arm swingingly secured to the top and engaging in the apertures of the rack as and for the purpose described.

3. In a locking device for telescopes, satchels, trunks and the like, a rack or racks secured to the body portion having upwardly inclined apertures, a brace secured to the 100 cover, and a shell or plate attached to the cover and carrying a locking-bar also inclined upwardly and adapted to engage in the apertures of the rack, all parts being arranged and operating substantially as shown and described.

In testimony whereof I affix my signature in presence of two witnesses.

THOMAS D. WALLACE.
